[57] CLAIM

The ornamental design for a stationary stand for containing visiting cards and memos, as shown and described.

DESCRIPTION

FIG. 1 is a perspective view of a stationary stand for containing visiting cards and memos showing my new design;

FIG. 2 is a top plan view thereof;

FIG. 3 is a bottom plan view thereof;

FIG. 4 is a rear side elevational view thereof;

FIG. 5 is a front elevational view thereof; and

FIG. 6 is a left side elevational view thereof, of which a right side elevational view would be a mirror image.

FIG. 1

FIG.2

FIG. 3

FIG. 5

FIG. 4

FIG. 6
